UNITED STATES PATENT OFFICE.

THOMAS JEFFERSON FOWLER, OF BIRMINGHAM, ALABAMA, ASSIGNOR, BY
MESNE ASSIGNMENTS, TO JOHN C. WESTBROOK.

COMBINED COTTON SWEEP, CHOPPER, &c.

SPECIFICATION forming part of Letters Patent No. 315,400, dated April 7, 1885.

Application filed September 10, 1884. (No model.)

To all whom it may concern:

Be it known that I, THOMAS JEFFERSON FOWLER, of Birmingham, in the county of Jefferson and State of Alabama, have invented 5 certain new and useful Improvements in Combined Cotton Sweeps, Choppers, and Dirlters, of which the following is a full, clear, and exact description.

Reference is to be had to the accompanying 10 drawings, forming part of this specification, in which similar letters of reference indicate corresponding parts in both the figures.

Figure 1 is a plan view of my improved 15 machine, parts being broken away. Fig. 2 is a sectional side elevation of the same, taken through the broken line $x x$, Fig. 1.

The object of this invention is to provide machines constructed in such a manner as to sweep or bar off the plants, chop them to a 20 stand, and dirt or hill them at one passage along the row, and which shall be simple and inexpensive in construction, and readily adjusted and controlled.

The invention consists in the construction 25 and arrangement of parts, as will be herein-after fully described and claimed.

A are the drive-wheels, one of which runs loosely upon and the other is rigidly attached to the axle B, so as to carry the said axle with 30 it in its revolution. The axle B revolves in bearings attached to the frame C, to the centers of the front cross-bars of which is attached the tongue D.

To hangers E, attached to the forward parts 35 of the side bars of the frame C, is journaled a shaft, F, the end parts of which are slotted longitudinally to receive the standards G. The standards G are adjustably secured in the slots of the shaft F by bolts or other suitable 40 means, and to the lower ends of the said standards G are secured the sweeps H, to bar off or sweep the sides of the row as the machine is drawn forward.

To the axle B is attached a gear-wheel, I, 45 the teeth of which mesh into the teeth of a smaller gear-wheel, J, attached to a short shaft, K.

The shaft K revolves in bearings attached to the frame C, and to its inner end is attached 50 a beveled gear-wheel, L, the teeth of which

mesh into the teeth of a beveled gear-wheel, M, placed upon the upper part of the vertical shaft N, and resting upon a bracket, O, attached to the frame C. The shaft N is connected with the beveled gear-wheel M by a 55 tongue and groove, so that the said shaft can be moved up and down while being carried around by and with the said gear-wheel in its revolution. The lower part of the shaft N revolves in bearings attached to the lower end 60 of a hanger, P, secured to the bracket O or to the frame C.

To the lower end of the shaft N, or to a head or hub attached to the said end, are attached four (more or less) radial arms, Q, to the outer 65 ends of which are attached or upon them are formed chopping-hoes or cutters R.

The upper end of the chopper-shaft N is swiveled to a coupling, S, to which is hinged the lower arm of an elbow-lever, T, which is 70 fulcrumed to a support, U, attached to the frame C, so that the shaft N and its arms Q and cutters R can be raised and lowered to regulate the depth at which the said cutters work 75 in the ground, and to raise the said cutters away from the ground when required.

The lever T, and with it the shaft N, arms Q, and cutters R, are held in any position into which they may be adjusted by a hook-pawl, U', which engages with the toothed edge of a 80 catch-bar, V, attached to the frame C.

To the rearwardly-projecting ends of the side bars of the frame C are attached hangers W, to which is journaled a shaft, X, the end parts of which are slotted to receive the 85 standards Y. The standards Y are secured adjustably to the shaft X by bolts or other suitable means, and to the lower ends of the said standards are attached the dirting-plows Z, the mold-boards or wings of which are so 90 shaped as to give the desired form to the hills.

To the shaft F, that carries the sweeps or barring-off plows, is rigidly attached an arm, a, to the outer end of which is hinged the forward end of a bar, b. The bar b extends back 95 into such a position that its rear end can be readily grasped by the driver from his seat to adjust the sweeps H. The lower edge of the rear part of the bar b has recesses c formed in it to receive the edge of the catch-plate 100

d, to hold the sweeps securely in any position into which they may be adjusted.

To the shaft X, that carries the dirting-plows, is rigidly attached an arm or lever, e, 5 which extends along a catch-bar, f, by which the said lever, and with it the shaft X, standards Y, and plows Z, are held in any position into which they may be adjusted.

g is a standard, the lower end of which is 10 attached to the center of the rear cross-bar of the frame C, and to its upper end is attached the driver's seat h.

Having thus described my invention, what I 15 claim as new, and desire to secure by Letters Patent, is—

In a combined sweep, chopper, and dirter, the combination, with frame C, the axle B, having a gear-wheel, I, the shaft K, parallel

with said axle, and having a gear-wheel, J, meshing with the gear-wheel I and beveled 20 gear L at its inner end, the bracket P, depending from the frame C, the vertical shaft N, loosely mounted therein, and provided with horizontal blades Q R on its lower end, the beveled pinion M, connected to shaft N by a 25 tongue and groove, and meshing with bevel-gear L, the coupling S, swiveled to the upper end of shaft N, the pivoted lever T, connected to said swiveled coupling, and the rack V, adapted to be engaged by said lever T, sub- 30 stantially as set forth.

THOMAS JEFFERSON FOWLER.
